UNITED STATES PATENT OFFICE

RAYMOND T. ROTH, OF NEW YORK, N. Y.

TERMINAL BLOCK

Application filed March 1, 1927. Serial No. 171,791.

This invention relates to terminal blocks and particularly to terminal blocks having a plurality of transverse partitions of insulating material separating the conductor connections.

The object of the invention is to provide a block of molded material adapted to receive interchangeably various terminal connecting means between the partitions and a further object of the invention is to provide a plurality of different terminal connecting means which will be simple, dependable and inexpensive and interchangeable with each other in the same block.

In the accompanying drawings illustrating the invention

Fig. 1 is a plan view of a block illustrating one embodiment of the invention,

Fig. 2 is a cross sectional view on the line 2—2 of Fig. 1,

Fig. 3 is a cross section on line 3—3 of Fig. 1,

Fig. 4 is a cross section on the line 4—4 of Fig. 1,

Fig. 5 is a cross section on the line 5—5 of Fig. 4.

Fig. 6 is a sectional view of a modification.

Figs. 7 and 8 are cross sectional views on lines 7—7 and 8—8 respectively of Fig. 6.

In the embodiment of the invention illustrated in the drawings the block 6 has end members 7 provided with holes 8 for screw or other means for fastening the block in place. Between the ends are the transverse partitions 9 providing between them the spaces or channels for the terminal connecting means.

In the block of this invention the ends 7 and partitions 9 have end enlargements 10 and central enlargements 11 strengthening the parts and serving as abutments to retain the terminal connecting means in the spaces between the partitions. Molded in the block are the internally threaded bushings 12 between the partitions and on each side of the longitudinal center line and these bushings serve to attach the terminal connecting means to the block, which is molded with a central depression 13 in the bottom of each

space to adapt the block for switch connecting means as shown in Figs. 2 and 4.

In Figs. 1 and 2 the block carries in the spaces to the left the screw switch and jack clamp designated generally at 14 and forming terminal connecting means between opposite sides of the block. This switching means comprises bent metal strips 15, 16 adapted to be fastened in place on the block by screws 17, 18 threaded into the anchor bushings 12 and acting also to receive and bind the wire terminals of the circuits to be connected. The strip 15 has its inner end upturned and provided with a screw 19 threaded through the strip so as to be adjustable into and out of contact with the downwardly bent end of the strip 16. The screw 19 will thus serve as a switch to make and break the connection between terminals held by screws 17, 18. The parts also cooperate to form a jack clamp adapted to hold a jack or tap 20 comprising flat conductor strips on opposite sides of an intermediate insulator so that the conductor strips are held in series between the terminals for testing purposes and the like.

Where no switch is desired the terminals are connected by a flat conductor strip 21 (as shown in Fig. 3) having the segmental lugs 22 struck up to serve as abutments and guides to retain the terminal wires from slipping out when gripped by the tightening of the screws 17, 18.

In connection with circuits where it is important to conveniently open and close the circuit as required the block of this invention provides a switch 23 adapted to be thrown open or closed. The switch clips 24, 25 have contact jaws 26 formed by bending of the strip metal into the form shown, and lugs 27 are punched out and bent downward and molded in a connecting block 28 of insulating material so as to accurately line and securely hold the switch parts. The connecting block 28 fits into the depression 13 when the clips are fastened in place by the screws 17, 18, and the clip 24 carries a pivoted blade 29 making and breaking contact with the jaws 26 of clip 25 and having a handle or finger 100

piece 30 molded on a projection 31 of the blade.

Instead of the pivoted blade 29 the switch means as shown in Figs. 6 and 7 may comprise a sliding strip 32 bent to provide the finger piece 33 and sliding in jaws 34, 35 of clip 24' and engaging and disengaging the jaws 36, 37 of clip 25'. A projecting lug 38 may be provided on the switch blade strip 32 to engage the end of the jaw 34 to prevent complete withdrawal of the blade and to indicate by engagement that the switch is completely open.

It is usually desirable to mark the various circuits of the block and for this purpose marking strips 40 may be provided set in recesses 41 of the partitions and fastened in place by screws 42. This marking strip must, of course, be discontinued over the sections of the block using the pivoted switch of Figs. 4 and 5. Instead the switch handle 30 will have molded in it a disk 43 of material adapted to be marked as desired.

The block is made of a single mass of molded material and this one form of block serves for all the different types of conductors in any desired combination on the block. It is only necessary to carry a stock of the blocks and to assemble with them the desired types of the conductors to suit each order. In use also the conductors are readily replaceable and interchangeable with each other as desired for changes in service. The separate parts of switch 23 and switch 23' (Fig. 6) are fixed in alinement with each other by the molding of their projections in the solid block 28, 28' of insulating material fitting into the recess 13. This recess 13 also accommodates the contacting portions of the switch shown in Fig. 2 the parts of which are held in place between the partitions in such manner as to effectively cooperate irrespective of exact alinement, so that the connecting block of insulation is dispensed with.

I claim:

45 1. A terminal block of an integral mass of molded insulating material comprising a series of transverse partitions with recesses at the bottom of the spaces between them and anchor devices molded in place between said partitions on each side of said recesses, and a plurality of different types of terminal connectors interchangeably fitting between said partitions and adapted to be fastened in place by attachment to said anchor devices to form current carrying conductors over said recesses.

50 2. A terminal block of an integral mass of molded insulating material comprising a series of transverse partitions with recesses at the bottom of the spaces between them and anchor devices molded in place between said partitions on each side of said recesses, and integral and separable switch terminal connectors interchangeably fitting between said partitions and adapted to be fastened in place

by attachment to said anchor devices to form current carrying conductors over said recesses.

55 3. A terminal block of an integral mass of molded insulating material comprising a series of transverse partitions with recesses at the bottom of the spaces between them and anchor devices molded in place between said partitions on each side of said recesses and a marking strip across the partitions, and integral and separable switch terminal connectors interchangeably fitting between said partitions and underneath said marking strip and adapted to be fastened in place by attachment to said anchor devices to form current carrying conductors over said recesses.

60 4. A terminal block of an integral mass of molded material comprising a series of transverse partitions with recesses between them and anchor devices molded in place between said partitions on each side of said recesses, a marking strip extending across the upper portions of said partitions, and a switching device extending under said marking strip and connecting opposite sides of said block between said partitions, each switching device having a portion extending into the corresponding recess and comprising a metal strip fastened to one of said anchor devices and having a portion formed to carry a movable switch member, and a second metal strip fastened on the other side of the block and having a portion cooperating with said switch member to make or break a circuit between the opposite sides of the block.

65 5. A terminal block of insulating material, comprising a series of transverse partitions forming narrow channels extending across the block, each channel being formed with a recess in its bottom and a plurality of terminal connectors of different types interchangeably mounted in said channels, one of said connectors being a switch comprising two metal strips secured at the bottom of said channel at opposite sides respectively of said recess, the inner end of one of said strips being bent downwardly into said recess and the inner end of the other strip being bent upwardly, and movable conducting means carried by the upwardly bent end and adapted to make and break contact with the downwardly bent end.

70 6. A terminal block of insulating material comprising a series of transverse partitions forming narrow channels extending across the block, each channel being formed with a recess in its bottom, a plurality of terminal connectors of different types interchangeably mounted in said channels, one of said connectors being a switch comprising two metal strips secured to the bottom of the channel at opposite sides respectively of the recess, the inner end of one of said strips being inclined upwardly and the inner end of the other strip being inclined downwardly into the recess; and movable conducting

means carried by the upwardly inclined end, adapted to make and break contact with the downwardly inclined end; and a marker extending across said channels and located above said switch, the movable conducting means of said switch being accessible for operation from one side of the marker.

7. A terminal block of insulating material, comprising a series of transverse partitions forming narrow channels extending across the block, each channel being formed with a recess in its bottom; a plurality of terminal connectors of different types interchangeably mounted in said channels, one of said connectors being a switch comprising two metal strips secured to the bottom of said channel, the inner end of one of said strips being inclined upwardly and the inner end of the other strip being inclined downwardly into said recess; a screw threaded through said upwardly inclined end and adapted to be turned to make and break contact with said downwardly inclined end; a marker extending across said channel above said switch and a conducting tap adapted to be clamped by said screw against said downwardly inclined end, said tap when so clamped extending upwardly at one side of said marker and said screw being accessible for turning from the other side of said marker.

8. A terminal block of insulating material comprising a series of transverse partitions forming narrow channels across the block, a marker secured across the top of the partitions intermediate their ends, a plurality of terminal connectors of different types interchangeably fitted within said channels, one of said connectors being a switch operable to make and break a circuit without removal of said marker.

9. A terminal block of insulation material comprising a series of transverse partitions forming channels across the block, a marker extending across said channels between their ends, a switch connector in a channel beneath said marker and having a contact movable longitudinally of said channel and accessible for operation at one side of said marker, whereby said switch may be operated without disturbing said marker and a connector of another type interchangeable with said switch in said channel.

10. A terminal block of insulation material comprising a series of transverse partitions forming channels across the block, a marker extending across said channels between their ends, and a switch connector in a channel beneath said marker and having a contact movable longitudinally of said channel and accessible for operation at one side of said marker, whereby said switch may be operated without disturbing said marker.

11. A terminal block comprising a series of transverse partitions with recesses between them, a marking strip extending across the

upper portions of said partitions and a switching device extending under the marking strip and connecting opposite sides of said block between the said partitions, each switching device comprising a portion extending into the corresponding recess and comprising a metal strip fastened to one side of the block and having a portion formed to carry a movable switch member and a second metal strip fastened on the other side of the block and having a portion cooperating with said switch member to make or break the circuit between the opposite sides of the block.

12. A terminal block comprising a series of transverse partitions, a marking strip extending across the upper portions of said partitions and a switching device extending under said marking strip and connecting opposite sides of said block between said partitions, each switch device comprising a metal strip secured to one side of the block and having an upwardly bent portion formed to carry a movable switch member located beneath said marker and a second metal strip fastened on the other side of said block and having a portion cooperating with said switch member to make or break the circuit between the opposite sides of the block.
